Primary Examiner — Shannon W Morgan*Assistant Examiner* — Altaira J Swangin(74) *Attorney, Agent, or Firm* — Lerner, David, Littenberg, Krumholz & Menlik, LLP(57) **CLAIM**

The ornamental design for a lip balm container, as shown and described.

DESCRIPTION

FIG. 1 is a front perspective view of the lip balm container; FIG. 2 is a front elevational view thereof; FIG. 3 is a rear elevational view thereof; FIG. 4 is right side elevational view thereof; FIG. 5 is a left side elevational view thereof; FIG. 6 is a top plan view thereof; FIG. 7 is a bottom plan view thereof; FIG. 8 is a front perspective view of a second embodiment of the lip balm container; FIG. 9 is a front elevational view of the embodiment shown in FIG. 8. FIG. 10 is a rear elevational view of the embodiment shown in FIG. 8. FIG. 11 is a right side elevational view of the embodiment shown in FIG. 8 (the left side being a mirror image of the right side elevational view); and, FIG. 12 is a top plan view of the embodiment shown in FIG. 8. The broken lines show portions of the lip balm container that form no part of the claimed design.
